UNITED STATES PATENT OFFICE.

HARRY M. JOHNSON, OF LIVERMORE, CALIFORNIA.

COMBINATION INSTRUMENT.

964,785.

Specification of Letters Patent. Patented July 19, 1910.

Application filed September 9, 1909. Serial No. 516,904.

To all whom it may concern:

Be it known that I, HARRY M. JOHNSON, a citizen of the United States, residing at Livermore, in the county of Alameda and State of California, have invented certain new and useful Improvements in Combination Instruments, of which the following is a specification.

This invention relates to new and useful improvements in combination instruments, and more particularly to a drafting instrument, which combines the features of a T-square, protractor, compass, gage, straight edge, and rule.

The principal object of my invention is to provide an instrument of the above character which is simply constructed and comprises but two principal elements which may be quickly adjusted with relation to each other to produce a device which is adaptable to any of the various uses above specified.

Another object is to provide an instrument which is ordinarily designed to be used as a T-square, the head of which may be readily positioned at any desired angle with relation to the blade, and has integrally formed therewith a protractor whereby the desired angle may be quickly determined.

A further object is to provide a device which may be quickly converted into a compass, a movable pin point being adjustable in a longitudinal groove or slot formed in the blade, the extreme end of said blade having an opening formed therethrough for the reception of a pencil.

With these and other objects in view, the present invention consists in the combination and arrangement of parts as will be hereinafter more fully described and particularly pointed out in the appended claims, it being understood that changes in the specific structure shown and described may be made within the scope of the claims without departing from the spirit of the invention.

In the drawings forming a part of this specification, and in which like numerals of reference indicate similar parts in the several views,

Figure 1 is a top plan view of my improved combination instrument. Fig. 2 is a vertical longitudinal section therethrough. Fig. 3 is an enlarged transverse section taken on the line 3—3 of Fig. 2. Fig. 4 is a detail perspective view of the blade.

Referring to the drawings 5 indicates the

blade of the instrument which is preferably constructed of hardened steel, and 6 the head thereof which is disposed upon one end of the blade and in transverse relation thereto. The head 6 is in the form of a rule 7 and a protractor 8 which is integrally formed therewith. Secured to the rule 7 there is a screw threaded bolt 9 which projects upwardly through a central longitudinal slot 10 provided in the blade 5. The head 6 is disposed beneath the end of the blade, and the slotted central portion of the blade is raised or elevated above the main side portions thereof as shown at 11. The opposite edges of the blade 5 are scaled or graduated as shown at 12, to provide a convenient measuring device. The bolt 9 has disposed upon its threaded portion thereof a binding screw 13 which is adapted to have frictional engagement with the surface of the raised portion of the blade, and rigidly secures the head 6 upon the end thereof.

The compass point 14 is slidably mounted in the groove 10, and is held in its adjusted position upon the blade 5 in the following manner; the pin is in the form of a cylindrical shank 15 which is provided at its upper end with the nurl head 16. The lower end of the shank is provided with exterior left hand screw threads which are adapted to engage with similar threads provided upon the interior of a sleeve 17. This sleeve is also provided at its lower end with the exterior right hand threads which engage with similar threads in the binding screw 18. The screw 18 has a reduced depending portion 19 which extends through the slot 10, and receives the washer plate 20. This plate is formed with a central opening 21 through which the pin point 14 passes when the shank 15 is rotated within the sleeve 17. As the lower end of the sleeve and the binding screw are provided with right hand threads, it will be obvious that any rotation of the sleeve will thus be prevented. The pin point will likewise be held in its adjusted position when the screw 18 is adjusted upon the blade 5. An indicator 22 is carried by the screw 18, and is adapted to be moved into registration with the graduations provided upon the blade. In this manner the radius of the arc or circle to be inscribed may be quickly and accurately determined. An opening is centrally formed in the outer end of the blade 5 to receive the pencil or other marking element 23.

After the pin point has been adjusted to the desired position upon the blade, it is forced through the paper or other working material, by pressure being brought to bear upon the head 16. The blade and head are then rotated, the binding screw 18 acting as a pivot therefor, and the arc or circle will thus be described upon the paper by the pencil 23. If desired the head 6 may 10 be entirely removed from the blade when the instrument is being used for this purpose.

The protractor 8 is provided with the usual degree graduations, and the adjacent 15 end of the blade 5 has formed thereon the pointer 24 which is adapted to be brought into registration with any one of these graduations, when it is desired to define any particular angle upon the drawing surface. 20 The inclination of beams, joist, or struts may also be quickly and accurately determined in a similar manner.

From the foregoing it will be seen that I have provided an instrument of great 25 utility in which is combined the features of a rule, protractor, compass, gage, T-square, and straight edge. When used as a gage the head 6 is positioned upon one edge of the work, and the point 14 brought into 30 register with the required graduation upon the blade, and the instrument moved over the work, the point 14 marking the surface thereof in the usual manner. It will be noted that but two principal elements are 35 employed, the protractor 8 and the rule 7 being integrally formed to provide the head of the T-square. The instrument is thus rendered very simple in construction and may be quickly converted to provide a device which is adaptable to the various uses 40 above set forth. It is extremely durable in use, being formed entirely of hardened steel, and is neat, light, and comparatively inexpensive to manufacture.

45 What is claimed is:

1. An instrument of the class described comprising a blade, having a longitudinal slot formed therein, a cross head arranged upon one end of said blade, a screw threaded 50 bolt carried by said head and projecting through a slot formed in said blade, a binding screw disposed upon said bolt, said cross head consisting of a graduated rule and protractor integrally formed therewith, said 55 protractor being provided with degree graduations, a pointer formed upon said blade adapted to register with the graduations on said protractor, a compass point longitudinally adjustable in the slot in said blade, 60 means for securing said point in its adjusted

position, scale graduations provided upon the opposite edges of said blade, a pointer carried by said compass point adapted to register with the graduations upon one side of said blade, and a pencil positioned in the 65 outer end of said blade.

2. An instrument of the class described comprising a blade having a centrally raised portion, said raised portion having a longitudinal slot formed therein and extending 70 substantially the entire length thereof, a cross head positioned upon one side of said blade, a screw threaded bolt carried thereby projecting through the slot in said blade, a binding screw disposed upon said bolt 75 adapted to secure the cross head to the blade, a compass pin adjustably mounted in said slot, said pin having a screw threaded shank portion, a nut head formed upon the upper end thereof, said shank having 80 threaded engagement in a cylindrical sleeve, a binding screw threaded upon the exterior of said sleeve, said screw having a reduced portion extending into said slot, a washer disposed thereon, said washer having a central opening therein to receive the compass point, and a pencil carried in the outer end of said blade.

3. An instrument of the class described comprising a graduated blade, a cross head 90 removably disposed upon one end of said blade, a protractor integrally formed therewith, a pointer carried by the blade adapted to register with the graduations of said protractor, said blade having a longitudinally 95 raised central portion, said raised portion having a longitudinal slot formed therein, a compass point adjustably mounted in said slot, said point having a left hand threaded shank portion, a sleeve provided with interior and exterior left and right hand threads respectively, said threaded shank being engaged with the interior threads of said sleeve, a binding screw engaged with the exterior threads on said sleeve and extending 100 through the slot in said blade, a securing plate engaged upon the end of said binding screw, a pointer carried by said screw adapted to register with the graduations on said blade, said blade having an 110 opening centrally formed through the outer end of said blade, and a pencil positioned in said opening.

In testimony whereof I affix my signature, in presence of two witnesses.

HARRY M. JOHNSON.
